UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,421**, dated September 16, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

A A are L-shaped figures, and B B rectangular figures placed at certain distances apart and in diagonal rows upon the background of the carpet. Ornamental stripes *a*, *b*, and *d* are arranged between said figures, as shown. The figures A have a checkered background. Rich bouquets of flowers are represented within the figures B. Other flowers embellish the figures A A and the remainder of the background and connect the several figures on the background. The border of the carpet con-

tains parts of the figures A, and also the figures B, as shown.

I claim—

1. The design for a carpet, consisting of the figure A, figure B, and intermediate figure *a*, substantially as shown.

2. The design for a carpet, consisting of the figure A, figure B, intermediate figure *d*, and connecting floral ornaments, substantially as shown.

3. The design for a carpet, consisting of the figure A, figure B, intermediate figure *b*, and connecting floral ornaments, substantially as shown.

4. The design for a carpet, consisting of the figures A B and stripes *a b d*, substantially as shown.

The above specification of my invention signed by me this 30th day of July, 1879.

HENRY HORAN.
